UNITED STATES PATENT OFFICE.

WILHELM RIEHM, OF AUGSBURG, GERMANY, ASSIGNOR TO THE FIRM: MASCHINEN-FABRIK AUGSBURG-NUERNBERG AKTIENGESELLSCHAFT, OF AUGSBURG, GERMANY, A CORPORATION OF GERMANY.

TWO-STROKE INTERNAL-COMBUSTION ENGINE.

Application filed January 12, 1925, Serial No. 1,971, and in Germany April 8, 1924.

This invention relates to two-stroke internal combustion engines of the kind in which scavenging air ports are formed in the relatively thin wall of cylinder liner 5 with the object of giving the current of scavenging air a certain direction of movement in the interior of the cylinder. In such engines it is found that the incoming scavenging air is not given sufficient guidance by 10 the walls of the ports with the result that the scavenging air does not flow in the direction intended.

According to the present invention, in order to remedy the above-mentioned defect, guide blades are arranged in front of the scavenging air ports so as to ensure a proper guiding of the scavenging air and force the scavenging air to flow in the desired direction within the cylinder.

20 In order that the said invention may be clearly understood and readily carried into effect, the same will now be described more fully with reference to the accompanying drawings in which Fig. 1 shows in cross section an engine cylinder having two different constructions of guide blades according to this invention and Fig. 2 shows in cross section an engine cylinder with adjustable guide blades.

25 *a* is the cylinder liner having scavenging air admission ports *b* which for instance are so situated that their centre lines converge to a point *c*. In view of the small thickness of the liner *a*, the walls of the ports, as aforesaid, provide an insufficient guidance 30 for the incoming scavenging air. This is indicated at the left-hand side of the drawing where it will be seen that, without the present improvement, a section *d* of the air current passes the inner port edge *e* before it 35 strikes the outer edge *f*. In order to rem-

edy this, in front of the ports *b* are arranged, in the direction of flow of the scavenging air jets, guide blades *g* which are either cast with the cylinder jacket as shown 45 at the right hand side of the drawing or, as shown at the left hand side, are inserted as separate plates. The latter construction has the advantage over the former that it is possible to alter the angles of setting of the 50 guide plates relatively to the ports so that the direction of flow of the scavenging air can be regulated to give the greatest efficiency. This adjustment can be effected in a similar manner to that of the guide blades 55 of the well known Francis turbine, the individual guide plates *g* being rotatable around fixed pins *h* and also being connected by pins *k* and slots *i* to a displaceable ring *l* by the adjustment of which the said plates 60 are turned around the said pins.

Having now particularly described and ascertained the nature of my said invention and in what manner the same is to be performed, I declare that what I claim is:

1. In a two-stroke internal combustion engine, a cylinder, a liner in said cylinder, a reservoir for scavenging air bounded on one side by said liner, slits in said liner for letting air from the reservoir into the cylinder, and guide blades before said slits for guiding the air before it enters said slits. 70

2. A two-stroke internal combustion engine in accordance with claim 1 in which the guide blades are inserted plates. 75

3. A two-stroke internal combustion engine in accordance with claim 1 in which the guide blades are adjustable.

The foregoing specification signed at Munich, Germany, this 19th day of December, 1924. 80

DR. WILHELM RIEHM.
